UNITED STATES PATENT OFFICE.

GEORGE W. RIVES, OF ROCHESTER, NEW YORK.

DESIGN FOR A FACE-PLATE FOR REGISTERS.

SPECIFICATION forming part of Design No. 21,123, dated October 20, 1891.

Application filed September 25, 1891. Serial No. 406,878. Term of patent 7 years.

To all whom it may concern:

Be it known that I, GEORGE W. RIVES, of Rochester, in the county of Monroe and State of New York, have invented a certain new and 5 useful Design for Face-Plates of Hot-Air Registers; and I do hereby declare that the following is a full, clear, and exact description of the same, reference being had to the drawing accompanying this application.

10 My design consists in the ornamental open-work or grating of the face-plate, as herein-after more fully described.

The drawing shows a plan or face view of the plate.

15 A indicates a border of the face-plate, which is in rectangular or square form and extends around the whole circuit. This border is composed of straight bars *a a*, with angular connecting-bars *b b*. At the corners of the border are square figures *c c*, with the angles set 20 in line with the border. In the center of each side of the border are circular figures *d d*, con-

sisting each of two circles, with a cross *f* forming the center. The central portion of the face-plate, within the bordering just described, 25 consists of an ornamental scroll-work *g*, of the form shown in the drawing.

Having described my new design, I claim—

The design for face-plates of hot-air registers, consisting of the bordering of straight 30 bars *a a*, extending around the outer edge, the square figures *c c* at the corners, the angles set in line with the bordering, the circular figures *d d* in the center of each side of the bordering, and the scroll-work *g*, forming 35 the central part of the grating, as herein shown and described.

In witness whereof I have hereunto signed my name in the presence of two subscribing witnesses.

GEO. W. RIVES.
